UNITED STATES PATENT OFFICE

97,008

DESIGN FOR AN AEROPLANE

Vernon Ray Grom, Buffalo, N. Y.

Application July 18, 1935, Serial No. 57,714

Term of patent 3½ years

To all whom it may concern:

Be it known that I, Vernon Ray Grom, a citizen of the United States, residing at Buffalo, in the county of Erie and State of New York, have invented a new, original, and ornamental Design for an Aeroplane, of which the following is a specification, reference being had to the accompanying drawing, forming part thereof.

Figure 1 is a view in side elevation of an aeroplane, showing my new design.

Figure 2 is a top plan view thereof.

I claim:—

The ornamental design for an aeroplane, as shown.

VERNON RAY GROM.
